US0D1081510S

(12) **United States Design Patent** (10) **Patent No.:** **US D1,081,510 S**
Kalha (45) **Date of Patent:** **** Jul. 1, 2025**

(54) **VEHICLE WHEEL RIM**

(71) Applicant: **VOLKSWAGEN AKTIENGESELLSCHAFT, Wolfsburg (DE)**

(72) Inventor: **Ranbir Kalha, Wolfsburg (DE)**

(73) Assignee: **VOLKSWAGEN AKTIENGESELLSCHAFT, Wolfsburg (DE)**

(**) Term: **15 Years**

(21) Appl. No.: **29/903,890**

(22) Filed: **Sep. 28, 2023**

(51) **LOC (15) Cl. 12-16**

(52) **U.S. Cl.**

USPC **D12/209**

(57) **CLAIM**

The ornamental design for a vehicle wheel rim as shown and described.

DESCRIPTION

FIG. 1 is a front elevation view of the vehicle wheel rim showing the present design; and,

FIG. 2 is a front, side perspective view thereof.

The broken lines depict portions of the vehicle wheel rim that form no part of the claimed design.

1 Claim, 2 Drawing Sheets
